UNITED STATES PATENT OFFICE.

MICHAEL J. SHEEHAN, OF NEW BEDFORD, MASSACHUSETTS, ASSIGNOR OF ONE-HALF
TO THOMAS J. CHARETTE, OF NEW BEDFORD, MASSACHUSETTS.

AUTOMATIC CONE AND TUBE GAUGE.

Application filed February 18, 1922. Serial No. 537,595.

To all whom it may concern:

Be it known that I, MICHAEL J. SHEEHAN, a citizen of the United States, and resident of New Bedford, in the county of Bristol and 5 Commonwealth of Massachusetts, have invented certain new and useful Improvements in Automatic Cone and Tube Gauges; and I do hereby declare the following to be a full, clear, and exact description of the invention, 10 such as will enable others skilled in the art to which it appertains to make and use the same.

The invention relates to a gauge attachment for cone and tube winding machines 15 of standard make, that will be effective in actuating the stop motion and arresting the operation of the winding machine when the cone or tube of thread or yarn has reached the desired diameter, the gauge device preferably comprising a rod-like element adapted 20 to be attached to and carried by a member of the winding machine having a movement commensurate with the increase in diameter of the cone or tube, as, for example, the cone 25 or tube holder or the door which carries the thread guide, according to the particular type of winding machine employed, said gauge rod having thereon an adjustable detent adapted to engage a suitable member 30 of the stop motion, when the cone or tube has been built up to the desired size and thereby move the gauge rod a commensurate distance.

The invention is illustrated in the accompanying drawings, in which:

Fig. 1 is a fragmentary perspective view of a cone or tube winding machine having the gauge device attached thereto;

Fig. 2 is a vertical elevation of the bar member of the gauge;

Fig. 3 is an edge elevation thereof, showing the detent in position; and

Fig. 4 is a plan view of the gauge showing the bar in section.

The invention is illustrated in Fig. 1 as applied to a so-called "universal" winding machine, of which a single cone or tube winding unit is shown, the same involving a cone holder 10, friction drive roller, thread guide, 45 tension and stop motion. As illustrated, the stop motion includes a pivoted member 11, which is normally actuated upon the breaking of the thread or the slackening of the tension thereon, by swinging the member 11 to the position shown in dotted lines. These

elements are characteristic of machines of this general type and require no specific description.

In operating machines of this general character, it has heretofore been necessary 60 for the attendant to stop each particular cone or tube to measure the diameter thereof by a hand gauge, which resulted in a material loss of time both to the operator and the machine, and, in case a particular cone or 65 tube was over-wound, necessitated the unwinding and rewinding thereof, with a possible damage to the thread or yarn. The stopping of the winding of any one of the cones or tube, in order to measure the diameter thereof, also damages the thread by causing an undue strain thereon, inasmuch as the manual stopping means does not release the tension device.

The present invention is intended to obviate 70 these difficulties and objections to machines of this type, and to provide means for stopping the individual winding units when the cone or tube of thread wound thereon has reached the desired predetermined diameter. As illustrated in the drawings, the attachment constituting the present invention includes a bar or strip of metal or other suitable material, 1, provided at one end with means for attaching it to a member of 75 the winding machine which has a movement commensurate with the increase in diameter of the cone or tube, in the instant machine, said member constituting the cone holder 10. As illustrated, the means for attaching the bar 1 to the cone holder 10 may conveniently take the form of a loop 5 formed in the end of the bar, provided with a bolt and nut to clamp the loop firmly about the cone holder and hold the bar in properly 80 adjusted position. The lower end of the bar is provided with a series of openings 9 adapted to receive the reduced end 7 of an angular detent or stop 2, the said detent being locked to the bar by means of a cotter 85 pin 6 passing through a hole in the reduced end 7 of the detent.

The angularly disposed arm of the detent projects under the trip element 11 of the stop motion so that when the bar member 1 is raised by successive steps, due to the increase 90 in diameter of the cone or tube, the said arm of the detent engages the under face of the trip device 11, as shown in dotted lines in Fig. 1, and actuates the stop mechanism, 100 110

which immediately arrests the operation of the machine. By adjusting the detent 2 in the proper hole 9 in the rod 1, it will be apparent that the rod and detent will constitute 5 an adjustable gauge which will accurately determine the diameter of the tube or cone, and stop the machine when the predetermined diameter has been reached.

While the particular form of the attachment 10 illustrated has been found effective and convenient, it will be understood that the invention is in no sense limited thereto, as the construction of the gauge, the manner of attaching the same to the movable part of 15 the winding machine, and the means for adjusting the detent on the bar, may be varied at will.

It is also to be understood that the device 20 is applicable to any of the standard type machines for winding cones or tubes, which involves a movable member of each winding unit, the movement of which is commensurate with the increase in diameter of the cone or tube, and to which member the gauge 25 device can be rigidly attached. For example, in another type of the universal machine, there is employed a door carrying the thread guide, which door moves commensurately with the increase in diameter of the 30 cone or tube, and in this type of machine the automatic gauge as described is rigidly attached to any suitable portion of the door element.

The particular advantages of the invention 35 as described are the insurance of substantial uniformity of diameter of the cones or tubes, facility of adjusting the gauge to produce cones or tubes of any desired diameter within the range of the machine, avoidance of undue strains and unequal tension 40 on the thread as the same is being laid up, and to materially increase the output of a given machine by avoiding the necessity of hand gauging and consequent stoppage of 45 the machine.

What I claim is:

1. In a cone and tube winding machine including a stop motion, a gauge device comprising a rod having means for attaching

the same to the cone or tube holder whereby 50 said rod will have a movement commensurate with the increase in diameter of the cone or tube, and a detent on said rod for engaging and actuating the stop motion when the cone or tube reaches a predetermined 55 size.

2. In a cone and tube winding machine including a stop motion, a gauge device comprising a rod having means for attaching the same to the cone or tube holder whereby said rod will have a movement commensurate 60 with the increase in diameter of the cone or tube, and an adjustable detent on said rod for engaging and actuating the stop motion when the cone or tube reaches a predetermined 65 size.

3. A gauge attachment for cone and tube winding machines comprising a rod having means for attaching the same to the cone or tube holder whereby said rod will have a movement commensurate with the increase in diameter of the cone or tube, and a detent on said rod adapted to engage and actuate the stop motion when the cone or tube reaches a predetermined 75 size.

4. A gauge attachment for cone and tube winding machines comprising a rod having means for attaching the same to the cone or tube holder whereby said rod will have a movement commensurate with the increase 80 in diameter of the cone or tube, and a detent adjustably mounted on said rod and adapted to engage and actuate the stop motion when the cone or tube reaches a predetermined size.

5. A gauge attachment for cone and tube winding machines comprising a rod having a clamping loop on one end for engaging the cone or tube holder and a series of spaced 90 openings on the other end, and an arm adapted to be secured in any one of said openings and to extend angularly from said bar to engage and operate a stop motion for the winding machine when the tube or cone reaches a predetermined size.

In testimony whereof I affix my signature,

MICHAEL J. SHEEHAN.
